Primary Examiner — Jennifer Rivard(74) *Attorney, Agent, or Firm* — Notaro, Michalos & Zaccaria P.C.(57) **CLAIM**

The ornamental design for a nail buffer, as shown and described.

DESCRIPTION

FIG. 1 is a front, top, left perspective view of a nail buffer showing my new design therefor;
FIG. 2 is a rear, top, right perspective view thereof;
FIG. 3 is a front elevational view thereof;
FIG. 4 is a rear elevational view thereof;
FIG. 5 is a side elevational view thereof;
FIG. 6 is a top plan view thereof;
FIG. 7 is a bottom plan view thereof; and,
FIG. 8 is an additional perspective view with the cap removed.
The broken lines illustrate portions of the nail buffer and form no part of the claimed design.
